UNITED STATES PATENT OFFICE.

FRITZ ALDENDORFF, OF BERLIN-WILMERSDORF, GERMANY, ASSIGNOR OF ONE-FOURTH TO PAUL KOLISCH, OF NEW YORK, N. Y.

AUTOMATIC TELEPHONE SYSTEM.

Application filed August 16, 1921. Serial No. 492,828.

To all whom it may concern:

Be it known that I, FRITZ ALDENDORFF, a citizen of the German Republic, residing at 23 Brabanterstrasse, Berlin-Wilmersdorf, 5 Germany, have invented certain new and useful Improvements in Automatic Telephone Systems, of which the following is a specification.

The following is a list of corresponding 10 foreign applications and patents filed more than one year prior to the date of filing this application: Germany, Patent No. 322,085 of June 5, 1914; Patent No. 308,302 of January 11, 1914, application G-41, 340 15 VIII/21^a3, filed March 20, 1914; Austria, application A. 7580/14, filed November 8, 1914; Switzerland, application G. 82,087, filed November 11, 1914.

This invention relates to a switching arrangement for automatic or semi-automatic 20 telephone exchanges.

One feature of the invention consists in calls being first extended from one point, line, or trunk to another point, line, or 25 trunk to a by-pass comprising, a line finder or the like with a plurality of collateral line-hunting elements or brushes all or a plurality of which are simultaneously in a state of readiness to seize a calling line and 30 to extend it to a said point line or trunk whereupon a second connection extending from the same calling line to the same point, line, or trunk is established through a second part which may include a switch or switches 35 of a different character.

Another feature of the invention consists 40 in a talking connection being established with the aid of two switches, used transitorily in establishing the connection, in such a way that the movable contacts of the one 45 said switch are set onto the fixed contacts of the line of the calling subscriber, and causes a talking connection switch to be set onto the calling line, whilst the movable contacts of the other said transitorily used switch causes a second talking connection switch to be set onto the line that 50 is to be called. The movable contacts of the transitorily used switches may be set both onto calling and called lines.

The arrangement may also be such that 55 the movable contacts of the talking connection switches may be set both onto the contacts of calling lines and onto the contacts of called lines, whilst two groups of transitorily

used switches are provided the one of which has movable contacts that can only be set onto the contacts of calling lines, whilst the movable contacts of the switches of the other group can only be set onto the contacts of called subscribers. In another modification two groups of talking connection switches and two groups of transitorily used switches are provided, and the movable contacts of one group of talking connection 60 switches transitorily used switches are only set onto calling lines, whilst the movable contacts of the other group of talking connection switches and transitorily engaged switches are only set onto called lines. 65

With the trunks that extend from the talking connection switches selector-finders may be associated which hunt for a transitorily used switch that is connected by a talking trunk finder to a free trunk. 70

If the transitorily used switches are divided into groups the number of identifying wires used for setting the talking connection switches onto calling or wanted lines needs only be as large as the number of 80 transitorily used switches present in each group.

Another feature of the invention relates to a circuit arrangement for conversation meters and consists in the meter current 85 path extending over a conductor that is separate from the connector used for selecting the wanted line. A further feature of the invention consists in an arrangement by which the called subscriber on lifting his receiver, closes a current path which includes a relay of the talking connection switch that has been set onto his line and a relay of the talking connection switch that has been set onto the calling line. 90

Another feature of the invention consists in an arrangement of the ringing current circuit, whereby the ringing current for calling the wanted subscriber flows over a conductor that is separate from the connector. 100

The switches used transitorily in establishing a connection are so arranged that, after the connection has been completed up to a certain point, they are immediately 105 restored to normal so as to be ready for further connections.

Another feature of the invention consists in identifying circuits of a special kind by means of which calling lines which 110

first extended to a certain trunk, line, or position through a by-pass or by-passes are subsequently connected without the possibility of confusion with other simultaneous 5 calls to the same trunk, line, or position through another path which may include switches of different characters from those included in the transitorily used by pass.

Still another feature of the invention 10 consists in circuits which enable calling lines to be extended through line finders without the aid of individual line relays.

The invention also includes circuit arrangements by which a rotary switch, after 15 it has been used to extend a connection to a trunk or line and its functions with respect to this trunk or line are completed, is in all cases caused to shift its wipers onto another trunk or line.

20 Another feature of the invention consists in switching arrangements by which one and the same switch is automatically changed from a switch of one character to a switch of another character.

25 These features and others not now specifically mentioned will be described fully hereinafter by way of example with reference to the accompanying drawings.

The invention is shown in the drawing. 30 Figs. 1 and 5 are diagrams which illustrate the fundamental method of establishing connections when the novel system is applied. Figs. 2, 3 and 4 show in detail the circuits of the switching apparatus used when the system takes the form shown in Fig. 1. Fig. 6 illustrates the layout of an exchange according to my invention in which group selectors are employed.

In Fig. 1 S^1 , S^2 are switches which set 40 their own wipers onto the lines of calling subscribers and then connect the latter through their associated talking trunk finder VS^1 , VS^2 to a free talking connection switch V^1 , V^2 , V^3 and a free selector finder WS^1 , WS^2 , WS^3 . When a subscriber, as T^1 , is connected through a switch, as S^2 , and its associated trunk finder, as VS^2 , to a free selector finder, as WS^3 , the selector finder WS^3 commences operating and hunts for a 50 free trunk, as t^1 , which is connected by another trunk finder, as VS^1 , to a free switch, as S^1 . The calling subscriber then sets the second switch S^1 onto the lines of the wanted subscriber, as T^3 . The talking 55 connection switch V^1 of the trunk t^1 then sets itself onto the wanted line T^3 . Meanwhile the talking connection switch V^3 sets itself onto the calling line also. When the two talking connection switches V^1 , V^3 have 60 set themselves onto the wanted and calling line respectively the switches S^1 , S^2 are thrown out of the connection and a talking connection for the two subscribers, which extends from T^1 through V^3 , t^1 , WS^3 , t^1 , V^1 to 65 T^3 , is maintained until the conversation is

concluded. The switches S^1 , S^2 , after they are thrown out of the connection, are immediately available for other connections.

The operations that occur in the various switches S , VS , WS , V of Fig. 1 in establishing a connection will now be explained in detail with reference to Figs. 2, 3 and 4. In these figures all the details of one single switch only of each kind are shown, because all switches of a kind have similar circuit arrangements. A coherent diagram of the circuits will be obtained if the Figs. 2, 3 and 4 are placed beside each other.

The switches S^1 , S^2 perform several functions. Firstly, they connect the calling subscriber to disengaged trunks (through their associated trunk finders VS); secondly, they select the line of a wanted subscriber and cause a talking connection switch V to set itself onto the wanted line. The switches S^1 , S^2 , on account of the variety of functions they perform, may be called "compound switches."

The mode of operation and significance 90 of all the other parts shown in the figures will be understood from the following description of the circuits and of the effects to which these circuits give rise.

Let it be assumed that the subscriber T^1 wishes to establish a connection with the subscriber No. 23.

On the calling subscriber lifting his receiver from the hook in the ordinary way, a current flows from the earth through a group relay GR to which all the subscribers of the group to which T^1 belongs are connected, and through the branch wire 1 of the bus bar 2, contact 3 of the cut off relay 4, line 5, T^1 , 6, contacts 7, resistance 8 to the negative pole of the battery. The group relay GR attracts its armature 9 and this brushes past the contact spring 10 causing a momentary contact between the springs 10 and 11. When the armature 9 subsequently falls back it again brushes past the contact spring 10. But this time the spring 10 is moved further away from the contact 11 so that no closure of the contact 10, 11 takes place.

It will be assumed that at the moment the subscriber T^1 calls, the compound switch S^2 is engaged. In such cases, for reasons that will appear from the detailed description of the compound switch S^1 , either the relay 12, which corresponds to the relay 14 of the compound switch S^1 , will be energized, or the off normal switch 15, which corresponds to the off normal switch 16 of the compound switch S^1 , will be in its off normal position. The former will be the case if the compound switch S^2 has just been taken into use for the purpose of establishing a connection with a wanted subscriber, and the latter will be the case if the compound switch S^2 has been taken into use for

the purpose of connecting to a calling line, or if the switch, after having been seized for the purpose of establishing a connection with a wanted line, has been moved out of its normal position.

Assume that the off normal switch 15 of the compound switch S^2 has been brought into its off-normal position. The contact 17 will then be closed and on the momentary closure of the contact 10, 11 a current will flow from earth through 11, 10, 19, 18, 20, 17, 21, 24, 25, driving magnet M of the compound switch S^1 , 26, 27 to the negative pole. The driving magnet is then energized and in attracting its armature it tensions a draught spring in a known manner. As soon as the current impulse caused by the momentary closure of the contact 10, 11 to flow through the magnet M ceases, the tensioned spring of the magnet M pulls the sets of brushes or wipers a^1, b^1, c^1, d^1, e^1 and a^2, b^2, c^2, d^2, e^2 of the compound switch S^1 out of its normal position and these sets of wipers are then caused to touch sets of contacts that are associated with different subscribers of the particular group of subscribers. As soon as the sets of wipers of the switch S^1 leave their normal position the off normal switch 16 goes into its off normal position, whereby a contact 28 is closed. This causes the interrupter 29 to be connected to the conductor 30 and the driving magnet M now receives current impulses which flow from the positive pole through 29, 28, 30, 25, M , 26, 27 to the negative pole of the battery. The sets of wipers of the compound switch S^1 are now caused to brush past the said contact sets until the wiper d of one of the sets of wipers touches a contact connected with the positive pole, as for instance until the brush d^1 meets the contact 31 which is connected through 7, 6, t^1 , 5, 3, GR with the positive pole or earth. The relay 32 will then be energized by a current which flows from the negative pole through 33, 34, 35, 36, coil 37, contact 38, d^1 , 39, 7, 6, 5, 3, 1, GR to earth. The relay 32 attracts its armature and in so doing closes the contact 39 and the contacts 40, 41, 42 and 43, whilst it opens the contacts 35, 38 and 26. By opening the contact 26 the relay 32 opens the circuit of the driving magnet M so that the sets of wipers are stopped moving. The opening of the contact 35 results in the battery lead to the energizing windings 37 and 44 of the test relays 32 and 45 being cut off. Hence it is never possible for more than one test relay 32 or 45 to be energized at the same moment or at one time. The opening of the contact 38 results in the current flowing through the energizing winding 37 being interrupted after a locking circuit including the winding 46 has been closed by the contact 39. The said locking circuit extends from the negative pole through the

contact 47, 49, 46, 39, c^1 , cut off relay 4 to earth.

The cut off relay 4 is also energized and opens its contacts 3 and 7, whilst it closes the contacts 49 and 50. The resistance of the winding 37 of the test relay 32 is such that it lowers the potential on the private normal leading to the compound switches or connectors to such an extent that the calling subscriber's line tests busy when other subscribers attempt to establish a connection with the busy calling line. The closure of the contact 41 results in a relay 52 being energized in a circuit which extends from the negative pole through 41, 53, 52, 54 to the positive pole. The relay 52 closes the contacts 55, 56 whilst it opens the contacts 34, and 54. By closing its contact 55 the relay 52 includes itself in a circuit that depends on the contact 58 of the off normal switch 16. By the opening of the contact 34 the battery lead through the contacts 33 and 34 to the test relays 32 and 45 is cut off so that, when the sets of wipers of the compound switch are subsequently moved round until they are restored to normal the said relays will be prevented from being energized in case the wipers d^1, d^2 brush over earthed contacts. A renewed energization of a test relay 32 or 45 can only take place after the sets of wipers have returned to their normal positions, because the opening of the contact 58 of the off normal switch, the interruption of the circuit (positive pole, 58, 55, 52, 46, 33, negative pole) which energizes the relay 52, and closure of the battery lead from the negative pole through 33, 34 and the contacts 35, 36 to the energizing windings 37 and 44 will only take place after the wipers have been restored to their normal positions.

The closure of the contacts 42, 43 of the test relay 32 and the simultaneous closure of the contacts 49, 50 results in the energization of the starting relay 59 of the selector finder WS^1 by a circuit which extends from the earth through the lower winding of the relay 59, contact 61, 62, 63, wiper 64 of the trunk finder VS^1 , which will have been set onto the trunk belonging to the talking connection switch V^1 in a manner hereinafter described, contact 43, $b^1, 50, 5, T^1, 6, 49, a^1, 42, 65, 66, 67, 68$, upper winding of the relay 59 to the negative pole. The relay 59 is thus energized and closes the contacts 69, 70, 71. The closure of the contact 69 results in the energization of the driving magnet M^1 of the selector finder SW^1 by a circuit which extends from the positive pole through 69, 230, $M^1, 72$ to the negative pole. The driving magnet M^1 now moves the wipers a^3, b^3, c^3 of the selector finder WS^1 and this movement continues until the wiper c^3 , which is connected to

the stopping relay 73, strikes a conductor 74 which belongs to a trunk that is connected by a trunk finder to a disengaged compound switch. The conductor 74 corresponds to 5 the conductor 74' which leads to the trunk of the talking connection switch V¹, and as all the trunks and the parts associated therewith have their circuits arranged in the same way, the functions which take place 10 in setting the selector finder WS¹ onto the trunk 74, 75, 76 may be explained on the assumption that the conductor 74' is the one that has been seized by the selector finder WS¹. Connected to the trunk that 15 has been found and seized by the selector finder WS¹ will be a compound switch (through a trunk finder VS) which is in its normal position. Since the circuits of 20 the compound switches are all arranged in the same way, it may be assumed for the moment, that S¹ is the compound switch that is connected to the trunk that has been seized. The stopping relay 73 is energized 25 when its brush strikes upon a trunk that is connected through a trunk finder to a compound switch that is in its normal position by a current which flows from the positive pole through 69, 73, c³, conductor 74 or 74', 75, 76, 77, 78, contact 79, relay 14 30 of the idle compound switch, resistance 80², contact 80 to the negative pole. The relays 73 and 14 are energized. The relay 73 opens the circuit of the driving magnet M¹ at 72, whilst the relay opens the contacts 33, 25, 79 and 21 and closes the contacts 82, 80', 81, 23, 22, 83, 84 and 85. By the closure of the contact 22 the starting wire 19, 87 leading from the group relay GR is connected to the prolongation 88 of the 40 starting wire that leads to the next compound switch so that a call from a further subscriber would result in the starting of the next compound switch.

By the opening of the contact 33 the lower 45 windings of the test relays 32 and 45 of the compound switch are disconnected from the battery so that these relays cannot be energized if the wipers d strike upon earthed test contacts. By the opening of the contact 25 and the closure of the contact 82 a new circuit is prepared for the driving magnet M of the compound switch which is to be set onto the wanted line in the manner of the type of switch, which, in known automatic systems, is named "a connector." The circuit that has thus been prepared for the driving magnet M is controlled by the dial impulse wire 89. By the closure of the contact 80' and the contact 23 a locking circuit 50 for the relay 14 is closed which extends from the negative pole through 80', 14, 23, 57 to the positive pole. The closure of the contact 81 results in the closure of a circuit extending from the positive pole through 81, 60, 90, 91, 92, relay 93, 94, 95 to the negative

60 pole in which the relay 93 is energized so as to close the contacts 96, 97, 98, 99, 197 whilst opening the contacts 100, 61, 60, 92 and 75. By the opening of the contacts 75 and 92 and the simultaneous closure of the contact 97 a 70 new circuit for the stopping relay 73 is closed which extends from the positive pole through 73, c³, 74', 97, 93, 94, 95 to the negative pole. The parts 69, 73, c³ and the parts 74', 97, 93, 94, 95 are, of course, located in 75 two different selector-or connector-finders, the parts 69, 73, c³ being located in the connector finder to whose trunk the calling subscriber is connected, whilst the parts 74', 97, 93, 94, 95 are located in the trunk that is connected through a trunk finder with an idle compound switch.

It must now be pointed out that the relay 59 which was energized in the manner already described by a flow of current through 85 the calling subscriber's instrument did not only start the operation of the associated connector finder WS¹, but also the operation of the associated talking connection switch V¹. The driving magnet M² of the 90 talking connection switch V¹ was energized by a current which flowed from the negative pole through 70, 101, M², 102 to earth. The driving magnet M² operates to move the wipers of a¹, b¹, c⁴, e⁴, e⁴ and this motion continues until the wipers reach the contact set of the calling subscriber T¹. A current then flows from the positive pole through 40, wiper e¹, identifying wiper e¹, identifying wiper e⁴, 106, winding 105 of the identifying relay, contact 107, identifying wire 108, identifying wiper 109 to the negative pole. The identifying relay is energized and opens the circuit of the driving magnet M² at the contact 102 so that the wipers stop 100 on the line ta, tb of the calling subscriber. By closing its contact 109 the identifying relay closes a locking circuit for itself which extends from the positive pole through the cut-off relay 4, 51, c⁴, 109, 110, 111, 112, 94, 95 to the negative pole. By its contacts 113 and 116 the identifying relay closes a dialling circuit which extends from the battery B in the compound switch connected to the trunk with which the connector finder WS¹ has established connection, contact 76² of this trunk, wiper a³ 115 of the connector finder WS¹, 119, contact 120 of the connector finder WS¹, 100, 121 (Fig. 3) 123 (Fig. 2) 115, a⁴, ta, 6, T¹, 5, tb, b⁴, 116, 124, 125 (Fig. 3), 60 (Fig. 4), 126, release relay 127 to the positive pole of the battery. Before the circuit of the impulse relay 118 120 which has just been traced was closed through the wipers of the compound switch V¹, another dialling circuit was closed which 125 may be traced as follows: battery B (Fig. 3) 130

in the compound switch connected to the trunk with which the connector finder WS^1 has established connection, impulse relay 118, 85, wire 101, 190, 65, 66, 67, 76, a^1 , 119, 5 conductor 66 of the trunk to which the connector finder WS^1 belongs which is connected to the calling line, the parts 65, 42, a^1 of the compound switch that has set its wipers onto the calling line, 49, 6, T^1 , 50, 10 the parts b^1 , 43, 64, of the compound switch the wipers of which have been set onto the calling line, or of the associated trunk finder 63, 126, release relay 127 to the positive pole.

It will be evident that in a system like 15 the present one in which a calling line 5, 6 is first temporarily connected through a bypass S to a certain trunk or switch WS^1 and is then connected over another path or switch V to the same switch WS^1 the second 20 switch V must be provided with some special means not merely for hunting for a line that in a calling condition but for identifying the particular calling line as a result of whose call it (i. e. the switch V) has been 25 starting operation. In other words a started switch V^1 must not set its wipers onto any calling line but only on the particular calling line whose call has been extended to it.

The means for enabling a switch or line 30 finder V to pick out a particular calling line amongst any number of calling lines comprises the identifying wires ek^1 , ek^2 , i , i_1 , ie_1 , 108, 104, and the identifying relays I_1 and I_2 . The identifying circuits are arranged in 35 such a manner that a wiper connected to the energizing winding of an identifying relay and traveling over a row of bank contacts can never encounter any line contact during its travel except a line contact belonging to the particular line upon which the wipers are to be stopped.

It will be seen from Fig. 2 that the bank contacts over which the wipers e_3 , e_4 of the line finder V_1 travel may be connected to 40 the positive pole of battery through the wires ek , ek_1 , the wipers e_1 and e_6 , and the wires i and i_1 . The switch S_1 can apply battery through e_1 only to ek , and the switch S_2 can apply battery through e_6 only to ek_1 . The 45 identifying wires ek and ek_1 multiplied in the banks of the line finders V_1 , V_2 etc. but not in the banks of the switches S_1 , S_2 . All the wires ek (one only is shown) emanating from the switch S_1 are connected to contacts travelled over by the wiper e_4 and similar wipers in other finders V_2 etc., whereas 50 all the wires ek_1 (only one is shown) emanating from the switch S_2 are connected to bank contacts travelled over by the wiper e_3 and similar wipers in other finders V_2 etc. Now if only two switches S_1 , S_2 be employed it will be evident that only one wire ek and only one wire ek_1 can be connected to battery at any certain moment. It will also 55 be obvious that current may be made to flow through the wire ek over the wiper e_4 of a certain switch V_1 or V_2 etc. only, if the wiper e_4 of this certain switch only is connected to battery. Similarly current may be made to flow through wire ek_1 over the 60 wiper e_3 of a second certain switch only, if the wiper e_3 of this second switch only is connected to battery. The function of connecting only the wiper e_3 of one switch or finder V and only the wiper e_4 of another 65 switch V to battery, so that only the wiper e_3 of a certain finder will encounter certain line wire ek_1 , and only the wiper e_4 of a certain second finder will encounter a certain line wire ek , is performed by the 70 switches VS_1 , VS_2 . Identifying wires 108, 104 which are not multiplied in these switches emanate from their contact bank. The wire 75 108 from switch VS_1 leads to through the top winding of the identifying relay I_1 to the identifying wiper e_4 and the wire 104 leads from the switch VS_2 through the lower winding of the identifying relay I_1 to the identifying wiper e_3 . Thus whether the wiper e_3 or e_4 of a finder V_1 , V_2 is connected 80 to battery or not depends upon whether the finder V_1 , V_2 or its corresponding trunk has been seized by the switch VS_2 or VS_1 . If the switch V_1 is seized by the switch VS_1 the identifying wiper e_4 will be connected to 85 negative battery over the top winding of the identifying relay I_1 , 108, 109, and ie_1 , but if the switch V_1 is seized by the switch VS_2 the other identifying wiper e_3 will be connected to negative battery over the bottom winding of the identifying relay I_1 , 104, 170, and ie_1 . So if a calling line is extended to the trunk associated with the finder V_1 through the switches S_1 and VS_1 the identifying wire ek will be connected to the positive battery pole and the wiper e_4 of V_1 will be connected to the negative pole. If at the same time another calling line is extended through the switches S_2 and VS_2 to the 90 trunk associated with the finder V_2 the identifying wire ek_1 will be connected to positive battery and identifying wiper e_3 of the finder V_2 will be connected to negative battery, so the finder V_1 will only be stopped 95 when its wiper e_4 strikes the bank contact of the calling line as a result of whose call it has started travelling, whilst the finder V_2 will only be stopped when its wiper e_3 strikes the bank of the particular second calling line whose call has caused it to operate. 100

The description of the operations involved in the connection desired by the calling subscriber T_1 will now be resumed.

If the calling subscriber sends in his selecting impulses before the talking connection switch V^1 has set its wipers onto his line, these impulses will flow over the path that has just been traced. After the talking connection switch has set its wipers onto the calling line the selecting impulses flow 105 110 115 120 125 130

through both of the above traced circuits simultaneously and through the impulse relay 118. When the relay 118 is energized a relay 128 which was energized by a current 5 from the negative pole through 84, 129, 128 to the positive pole is short circuited by the contact 132. The relay 128 is deenergized, but no effect is caused hereby at this time. The relay 133 is energized, when the relay 10 118 attracts his armature, by a current which flows from the negative pole through 133, 132 to earth and opens the contact 134, whilst it closes the contact 135.

As the calling subscriber wishes to call 15 subscriber No. 23 he sends in the digit "2" and thus causes the interruption of the dialling circuit. At each interruption the relay 118 lets its armature drop back and at each retraction of the armature a current flows 20 from the negative pole through 84, 130, 135, 89, 136 (Fig. 2), primary magnet ZM to the positive pole. The primary magnet moves the wipers 137, 138 onto the second set of contacts 139, 140. This set of contacts is 25 connected to conductors which lead to the test relay of the particular set of wipers of the compound switch that wipes over the group of contact sets in which the contact set of the wanted subscriber is located. After the calling subscriber has thus selected the tens 30 group of the wanted subscriber a short pause ensues during which the relay 118 keeps its armature attracted. Hereby the relay 128, which, is energized during the interruptions 35 of the dialling circuit by a current that flows from the negative pole through 84, 133, 128 to earth, is short-circuited and lets its armature drop back. This results in a closure of the contact 141 and in a subsequent 40 interruption of the contact 142, and a current impulse flows from the negative pole through 84, 131, 142, 141, 143, 144, 145, contact 146 (Fig. 2) which was closed when the wipers 137 and 138 were moved off their normal 45 positions, relay 147 to the positive pole. The relay 147 is thus energized and closes a locking circuit for itself which extends from the positive pole of the battery through 148, contact 83 to the negative pole. At the same 50 time the relay 147 opens a contact 136 whilst it closes a contact 149. The calling subscriber now sends in the second digit, which, as the line he desires is No. 23 is "3", so that he causes three interruptions of the dialling 55 circuit. At each interruption a current flows from the negative pole through 84, 130, 135, 89, 149, 82, magnet M, 26, 27 to the negative pole. The sets of wipers of the compound switch are caused to take three rotary steps 60 so that the set of wipers selected by means of the primary magnet ZM is set onto the contact set of the wanted line number 23. The rotary movement of the sets of wipers a^1 , b^1 , c^1 , d^1 , e^1 etc. of the compound switch set onto 65 the wanted line results in the associated off

normal switch 16 being moved out of its normal position. By this means the change-over circuit which includes the relay 147 is opened at the contact 144, whilst a test circuit is prepared at the contact 145 or a busy 70 tone circuit is prepared at the contact 146. At the same time a locking circuit for the relay 52 of the compound switch is prepared at the contact 58.

After the calling subscriber has caused the 75 wipers of the compound switch to be set onto the wanted subscriber's line in the manner described, another pause ensues during which the relay 118 keeps its armature pulled up and causes the relay 128 to deenergize. This results in the closure of the contact 152 and in the subsequent opening of the contact 153, and a test current flows from the earth through the cut off relay of 80 the wanted subscriber, wiper c^2 , which is set 85 onto the test wire of the wanted subscriber, contact 139 of the tens selector, wiper 137, coil 155 (Fig. 3), contact 153, 152, 145, 138, 140, winding 156 of the test relay 45 associated with the wiper c^2 , conductor 157, contacts 48, 47 to the negative pole. If the wanted subscriber is disengaged the relays 155 and 45 will be energized. The relay 45 closes its contact 158 and thus closes a locking 90 circuit for itself which extends from the negative pole through 47, 48, 157, 156, 148, c^2 , test wire of the wanted subscriber, cut-off relay of the wanted subscriber to earth. At the same time the closure of the contact 158 95 effects the short circuiting of the left winding of the relay 155. But this relay remains energized by a locking circuit which extends from the positive pole through its right winding, 159, 83 to the negative pole. On energizing the relay 155 closes a contact 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

to the wanted line and the compound switch that has been set onto the wanted line is established through the trunk finder VS_2 , the lower winding 103 of the relay of the talking connection switch will be connected through the wiper 170 of the trunk finder VS_2 to the negative battery pole and the identifying relay of the talking connection switch can only be energized if the identifying wiper e_3 strikes upon the identifying wire ek_1 which is connected by a wiper e_6 and a contact 171 of the compound switch S_2 belonging to the trunk finder VS_2 to the positive pole. Such a co-operation of a talking connection switch with a compound switch S_2 would of course only occur if the compound switch S_2 is not engaged at that particular moment and if the same is connected by its trunk finder to the particular talking connection switch V with which the connector finder WS_1 has established connection. If there are more than two compound switches S_1 , S_2 , there will be more than two identifying wires ek , ek_1 , leading to the fixed contacts of the talking connection switches V_1 , V_2 etc. As has already been pointed out, a special identifying wire leads from each compound switch S_1 , S_2 etc. to the talking connection switches V_1 , V_2 . The identifying relay of the particular talking connection switch V which is set onto the wanted line is thus energized through a different identifying wire from the one which leads to the compound switch that is set onto the calling line, this energization taking place through an energizing circuit that leads to the compound switch which has been set onto the wanted line in the manner already described. At the moment when the identifying relay is energized in consequence of its wipers striking upon the line of the wanted subscriber, the starting relay 172 of the trunk finder which belongs to the compound switch that has been set onto the wanted line is energized by a current which flows from the negative pole through 117, 174, contact 175 of the off normal switch 176, wiper 177, 172, to earth. In addition to this the starting relay 172 of the trunk finder which belongs to the switch that has been set onto the calling line is energized by a current which flows as follows: from the negative pole through the contact 117 of the talking connection switch set onto the wanted line, 174, 178, wiper d_3 of the connector-finder WS_1 , contact 179 of the off-normal switch 176 of the connector finder WS_1 which has been moved out of its normal position, wiper 177 of the trunk finder that belongs to the switch which has been set onto the calling line, relay 172 to the positive pole. The two relays 172 of the two trunk finders are thus energized simultaneously and close their contacts 180, 181, whilst opening their contacts 47 and 182. By the clo-

sure of the contact 180 circuits are closed in the two trunk finders which extend from the negative pole through the interrupter 183, contacts 180, driving magnets 184 to earth. By this means the wipers of each of the two trunk finders are set in motion and this motion continues until the wipers 185 strike upon conductors 186 which are not connected with the negative pole of the battery. The conductor 186 belonging to each trunk will be connected to the negative pole of the battery if one of the relays 59 or 93 is energized, or in the case of the off normal switch 176 being out of its normal position. The conductor 186 of a trunk will also be connected to the negative pole of the battery if some other trunk finder has previously seized it. In such a case the connection between the conductor 186 and the negative pole would be established through the contact 182 and the wiper 185 of the particular trunk finder which had previously seized the trunk. As long as the wipers of a started trunk finder continue striking upon the contact sets of previously seized trunks the relay 172 of the hunting trunk finder remains energized by a current which flows from the negative pole of the battery through the conductors 186, wiper 185, contact 181, relay 172 to earth. But as soon as the wiper 185 reaches a conductor 186 which belongs to a trunk that is not being used for conversation and that is not engaged the connection between the negative pole and the particular conductor will be missing and the relay 172 will be deenergized. As soon as the armature of the relay 172 falls back it will establish a connection at its contact 182 between the conductor 186 of the free trunk and the negative pole of the battery so that other trunk finders will now no longer be able to stop upon the seized trunk. When the armature of the relay 172 falls back the contact 180 will be opened, whereby the circuit of the driving magnet 184 of the trunk finder is interrupted and the wipers of the trunk finder are stopped.

The operations which occur in setting a trunk finder that belongs to the compound switch set onto the calling line onto a free trunk, and the operations involved in the seizure of a free trunk by the trunk finder belonging to the compound switch which has been set onto the wanted line are precisely similar.

As soon as the starting relay of a trunk finder is energized the opening of the contact 47 causes the interruption of the locking circuit of the particular test relay 32 or 45 of the associated compound switch. In the compound switch which is set on the wanted line a circuit is closed for the driving magnet M which extends from the positive pole through 29, 28, 25, M , 26, 27 to the negative pole. Since the battery leads to the relays

32, 45 etc. is open at the contact 34 no energization of the relays 32, 45 etc. take place when the wipers of a compound switch are moved past the contacts of other lines.

5 Hence the driving magnet M remains energized until the wipers are restored to their normal position and the off normal switch 16 is restored to normal. When this has taken place the contact 28 will be opened 10 and the interrupter 22 will be disconnected from the magnet M. At the same time the locking circuit of the relay 52 will be interrupted at the contact 58 and the battery lead from the negative pole through 33, 54 15 to the test relays 32, 45 will be reestablished. The relay 52 was energized by a current which flowed from the negative pole through contact 191, 53, 52, 54 to the positive pole.

It must be mentioned that at the moment 20 when the relay 172 was energized a contact at the point indicated by the numeral 190 in the conductor leading to the impulse relay 118 was opened and that the current flowing through the impulse relay 118 was 25 thus interrupted. When this happens this relay causes the relay 133, which was deprived of current by the opening of the contact 84 to be short circuited by the contact 129 so that it opens the contact 135 and 30 closes the contact 134. The closure of the contact 134 results in the energization of the release magnet 192 of the tens selector and in its restoration to normal by means of a current which flows from the negative pole 35 through 134, 193, 192 to the positive pole. When the armature of the relay 133 falls back the locking circuit of relay 14 which extends from the negative pole through 80', 14, 23, 57 to the positive pole is opened. 40 This is caused by the armature of the relay 133, in falling back, brushing past the contact spring 57 and momentarily opening the contact closed by this spring. This causes the de-energization of the relay 14. By the 45 opening of the contact 83 of the relay 14 belonging to the compound switch set onto the wanted line, the locking circuits of the relays 155 and 147 are opened so that these 50 relays are energized. All the parts of the compound switch, which was set onto the wanted line, will now have been restored to their normal positions.

At the moment when the relay 172 of the 55 trunk finder associated with the compound switch that is set onto the calling line is energized, the opening of the contact 47 of the said trunk finder causes the de-energization of the particular test relay 32 belonging to the set of wipers that is set onto the calling line. The contact 26 is then closed and the driving magnet M of the compound switch is energized by a current which flows from the negative pole to the contact 27, 26, M, 25, 28, interrupter 29 to the positive pole 60 of the battery. The driving magnet M now

moves the wipers of the compound switch past the fixed contact sets or bank contacts of the compound switch until they are restored to normal, when the circuit of the driving magnet will be interrupted by the 70 restoration of the off normal switch and the opening of the contact 28 caused hereby. During the motion of the wipers into their normal position the battery lead to the energizing winding of the test relays 32, 45 is 75 open at the contact 34 so that no stoppage of the compound switch is liable to take place by the energization of a test relay. The battery lead to the test relays is only 80 re-connected through the contacts 32, 34 of the test relays due to the opening at contact 58 of the locking circuit of relay 52 extending through 54 and 58, when the compound switch is restored to its normal position.

It will appear from the above description 85 that as soon as a talking connection switch has set its wipers onto the calling line and another talking connection switch has set its wipers onto the wanted line the two compound switches which took part in the establishing of the connection are immediately 90 restored to their normal positions and become available for other connections. The arrangement could also be such that in cases 95 where a talking connection switch sets its wipers onto the calling line before the selecting impulses are passed on to the compound switch that is to be set onto the wanted line, the compound switch which has 100 made connection with a calling line is thrown out of the connection before the second compound switch is set onto the wanted line. In such cases the selecting impulses 105 or some of them might flow over the wipers of the talking connection switch set onto the calling line.

When the relay 172 of a trunk finder is 110 energized in the manner described above it is kept energized by a current that flows from the earth through 172, 181, 185, 186 and thence either over the contact 71 or 96, or through the wiper of another trunk finder and through the relay contact 182 of this other trunk finder to the negative pole. This 115 current will, as has already been said, flow through the relay 172 until the wiper 185 of the trunk finder strikes upon a conductor 186 which is not connected to the negative pole of the battery, i. e. a conductor 186 which belongs to a trunk which is neither 120 being used for conversation nor has been seized by another trunk finder. The relay 172 then allows its armature to fall back and by opening the contact 180 deenergizes 125 the driving magnet 184. The wipers of the trunk finder will then connect the associated compound switch with a free, unused trunk which may now be used for another talking connection.

130 After the compound switches have been

thrown out of the connection the talking subscriber will be supplied with current which flows from the positive pole through the relay 127 (Fig. 4), 126, 60, conductor 5 125, b^6 , 124, 116, b^1 , t^2 , 5, T^1 , 6, ta , a^4 , 115, 123, conductor 121, 100, 120, 110, a^5 , contact 76 of the trunk which is connected by its associated talking connection switch to the wanted line, contact 67 of this line, 196, 197, 10 retardation coil 198, contact 199 (Fig. 2) to earth 200. The earth 200 was connected through the retardation coil 198 only at the moment when the talking connection switch set its wipers onto the wanted line. 15 At the moment when the talking connection switch set its wipers onto the wanted line a circuit was closed at the contact 113 for the ringing relay 114 which extends from the positive pole through 113, 114, 201, 20 interrupter 102 to the negative pole. The relay 114 now intermittently closes the contacts 203, 204 and at each closure of these contacts a ringing current is sent from the ringing current generator LM through 203, 25 115, a^4 , ta , 6, T^1 , 5, tb , b^4 , 116, 204 back to the ringing current generator. When the called subscriber lifts his receiver from the hook and the contacts 123, 124 are closed, a current will flow from the earth through the 30 upper winding of the relay 210, contact 99, conductor 121, 123, 115, a^4 , ta , 6, T^1 , 5, tb , b^4 , 116, 124, 125, 98, contact 211, 62, contact 75 onto which the connector finder has set its wipers that is associated with the talking 35 connection switch that has established connection to the calling line, wiper b^3 of the connector finder, contact 213, relay 212 of a connector finder to the negative pole. The relay 210 associated with the trunk connected to the called subscriber and the relay 212 associated with the trunk connected to the calling subscriber are energized simultaneously. The relay 212 establishes a new transmitter feed circuit for the calling subscriber which extends from the negative pole through 212, 215, 120, 100, 121 (Fig. 4), a^6 , 123 (Fig. 2), 115, a^4 , ta , 6, T^1 , 5, tb , b^4 , 116, 124, b^6 , 125 (Fig. 3), 60, (Fig. 4), 126 and through 127 to the positive pole. At 40 its contact 213 the relay 212 opens the current path leading through the wiper b^3 to the called subscriber. A new current path is now closed for this subscriber through the relay 210 which may be traced as follows: from the earth in the trunk which is connected to the called subscriber through the upper winding of the relay 210, contact 99, 121 (Fig. 3), a^6 , (Fig. 2), 123, 115, a^4 , ta , 6, t^1 , 5, tb , b^4 , 116, 124, b^6 , 125 (Fig. 3), 98, (Fig. 4), 217, lower winding of the relay 210 to the negative pole. By opening the contact 201 the relay 210 interrupts the circuit of the ringing relay 114 and the calling subscriber will now have a talking connection with the called subscriber which

may be traced as follows: from the calling subscriber T^1 , line 6, ta , wiper a^4 of the talking connection switch set onto the calling line, 115, 123, a^6 , 121 (Fig. 3), 100 (Fig. 4), 120, condenser 220, wiper a^3 , contact 76 of the trunk which is connected by its associated talking connection switch to the called subscriber's line, 67, condenser 218 (Fig. 3), contact 115 (Fig. 2) of the talking connection switch set onto the called line, wiper a^4 of this talking connection switch, conductor ta of the called subscriber's line, conductor 6, called subscriber's station, 5, conductor tb of the called line, b^4 , 116, 124, condenser 219 (Fig. 3), contact 62 (Fig. 4), 80 contact 75², wiper b^3 of the connector finder associated with the talking connection switch set onto the calling subscriber's line, contact 216, condenser 222, 126, 60, 125 (Fig. 3), b^6 , 124 (Fig. 2), contact 116 of the talking connection switch set onto the calling line b^4 of this talking connection switch, conductor tb of the calling line, conductor 5 back to the calling subscriber's instrument T^1 . When the called subscriber at the end of the conversation replaces his receiver on the hook in the ordinary way the relay 210 associated with the trunk connected to the called line is de-energized. When the armature of the relay 210 falls back the contact 94 is momentarily opened and the locking circuit of the relay 93 is thus interrupted. It will be remembered that this locking circuit extends from the negative pole through the contact 95 of the trunk that was connected to the called line and through the contact 94, relay 93, contact 97, 74', test contact, wiper c^3 of the connector finder associated with the talking connection switch set onto the calling line, test relay 73 to the positive pole. 95

The momentary opening of the contact 94 also deprives the winding 105 of the identifying relay of the talking connection switch set onto the called line of its connection with the negative pole through the contact 111, so that the said identifying relay is de-energized. At the same time the cut-off relay 4 of the called subscriber which was energized by a circuit which extended from the earth through 4, 51, c^4 , 109, upper winding of the identifying relay, contact 111, conductor 112, contact 94, 95 to the negative pole, is de-energized. All the parts belonging to the trunk connected to the called subscriber have now been restored to normal. 100

When the calling subscriber replaces his receiver the relays 127 and 212 of the trunk connected to the calling line are de-energized. On the de-energization of the relay 212 which was energized when the called subscriber responded, the armature 225 in brushing past the contact 223, caused the negative pole of the battery to the directly 115 120 125 130

connected to the wiper c^4 of the talking connection switch set onto the calling line. By this means the current flowing through the conversation meter Z (Fig. 2) of the calling line (earth, Z, 51, c^4 , 109, 105, 111, 112, 94, 95, negative pole) is strengthened to such an extent that the meter Z is energized and the finished conversation recorded. By the de-energization of the slow acting relay 127 the locking circuit of the identifying relay of the talking connection switch set onto the calling line is opened so that this relay and also the cut-off relay 4 and the meter Z are de-energized. At the same time the driving magnet of the connector finder WS¹ is energized by a circuit extending from the earth through 102, off normal contact 227, driving magnet m^1 , 72, to the negative pole. When the connector finder is restored to its normal position the contact 227 and hence the circuit of the magnet M¹ is opened so that the wipers a^2 , b^2 , c^2 are stopped. All parts of the switches used for the connection have now been restored to normal. The talking connection switches have no definite normal position. The connector finders can also be arranged so as to have no definite normal position.

To provide for cases in which a wanted line is found engaged when a compound switch is set onto the same a busy tone device 250 is furnished. If the wanted line is engaged the relay 155 does not get sufficient current to be energized and the busy tone device is connected through the contacts 251, 146, 154 to the dialling circuit leading to the calling subscriber. The calling subscriber then receives a busy signal which causes him to replace his receiver. This causes the de-energization of the impulse relay 118 in the compound switch set onto the called line and of the relay 127 associated with the trunk connected to the calling subscriber, and results in the restoration of the used apparatus to normal.

In the above described form of the invention each talking connection switch is connected to a simple connector finder. In larger exchanges group selectors could be provided in place of the connector finders which perform their operations before the compound switches carried out their selecting function. Another modification of the invention may comprise, instead of the compound switches which operate either to connect a calling subscriber to an unseized line or to select a called subscriber, two special sets of switching apparatus of which the one set operates to connect the calling subscriber to unseized trunks whilst the other set is only used for selecting the wanted subscriber's line.

A layout diagram of this modification is given in Fig. 6. The switches s_1 , s_2 represent the switching devices by which calling

subscribers are connected to free trunks lg_1 , lg_2 , lg_3 , and the switches LW_1 , LW_2 represent the apparatus which are used only for selecting wanted subscribers' lines and will therefore be called wanted line selectors. The switches s_1 , s_2 are preferably constructed in the form of quick-acting switching apparatus, such as relays or quick-acting line finders, and are connected through trunk finders VS_1 , VS_2 with free unseized trunk lines lg_1 , lg_2 , lg_3 leading to group selectors. Each wanted line selector LW_1 , LW_2 is always kept in connection with a free trunk l_1 , l_2 , l_3 , l_4 by its associated finder VS_1 , VS_2 in the same way as the temporarily engaged switches of Figs. 1-4. The trunks l_1 , l_2 , l_3 , l_4 are connected by intermediate switches ZV_1 , ZV_2 , ZV_3 , ZV_4 with other free trunks lg_1 , lg_2 , lg_3 . The trunks l_1 , l_2 , l_3 , l_4 are connected to the subscribers' lines by talking connection switches V_1 , V_2 , V_3 , V_4 . When a subscriber T_1 calls he is connected by a quick-acting finder (such as S_2) and its associated trunk finder V_2 with a free trunk such as lg_2 . By means of dialling impulses the calling subscriber then sets the group selector GW_2 onto the wanted group, say the group to which the trunks f_1 , f_2 , f_3 , f_4 lead. The group selector GW_2 then hunts for a free trunk which has been seized by a trunk finder, say the finder VS^1 . It will be supposed that this is the trunk l_1 . The calling subscriber now sends in further dialling impulses by which the wanted line selector is set onto the desired line, say T_3 . The switch V_1 associated with the trunk l_1 is now caused to set its wipers onto the line of the wanted subscribers T_3 which is identified by the wanted line selectors LW_1 . When the calling subscriber T_1 was connected through the switches S_2 and VS_2 to the trunk lg_2 a free intermediate switch, say ZV_2 associated with a trunk that had not been seized by a finder VS^1 , VS^2 was caused by suitable means to set its wipers onto the trunk lg_2 whereupon the switch V_2 associated with the trunk l_2 establishes a connection with the line of the calling subscriber T_1 .

When the switch V_1 has set its wipers onto the line of the wanted subscriber T_3 a talking connection is established which extends from T_1 through v_2 , l_2 , ZV_2 , lg_2 , GW_2 , f_1 , l_1 , V_1 to the wanted subscriber T_3 . As soon as this connection is established the switches S_2 , LW_1 are disconnected from the talking connection and connected by their associated trunk finders VS_2 , VS^1 to other free and unseized trunks.

For cases in which the calling and called subscribers are both in the same group the arrangement may be such that the group selector, when set onto the wanted group (which in this case will also be the group in which the calling subscriber is located),

effects a special switching function by which the talking connection instead of being established through the bank contacts leading to the various groups is confined to a local path within the group in which the call has originated. This local path may be established by causing the two intermediate switches, say ZV_1 , ZV_2 (associated with the switches V_1 , V_2 whose wipers are set onto the calling and, called lines respectively) to both set themselves onto a free multiple wire.

With switches of the kind described with reference to Fig. 6 a semi-automatic system could be built in which each switching apparatus which is used only for connecting the calling subscribers with unseized trunks is associated with a dial switch or selecting impulse sender for controlling the selectors.

The compound switches which perform a double function are advantageous in large exchanges in that the efficiency of the exchange is increased in cases where the calls are chiefly either outgoing calls or incoming calls.

Another form of the invention is shown in Fig. 5. In this figure $V1, V1^1-V2, V2^1-V3, V3^1-V4, V4^1$ are pairs of talking connection switches which are adapted to establish connections between any two subscribers T^1, T^2 etc. S^1, S^2 are line finders or switches which, when a subscriber makes a call, set their wipers onto the called line, and W^1, W^2 are selectors which operate to select the wanted line. VS^1, VS^2 are trunk finders which connect their pairs of switches S^1, W^1 or S^2, W^2 respectively to unseized pairs of talking connection switches. Hence each pair of switches SW is always connected to a free pair of talking connection switches.

Assuming that a subscriber T^2 calls with the intention of establishing a connection with a subscriber T^3 . When the subscriber T^2 makes the call a free switch S^1 sets its wipers onto the calling line C^2 . When the selector W^1 associated with the switch S^1 is subsequently set onto the wanted line T^3 by the digits sent in by the calling subscriber the talking connection switch $V3$, which is connected by the trunk finder VS^1 to the line finder S^1 , sets its wipers onto the calling line. After the selector W^1 has been set onto the wanted line C^3 the talking connection switch $V3^1$ associated with the talking connection switch $V3$ is caused to set its wipers onto the wanted line. When the talking connection switch $V3^1$ has set its wipers onto the selected line, the trunk finder VS^1 connects the pair of switches S^1, W^1 with some other pair of free talking connection switches and the selector W^1 is caused to return to normal.

65 The switching arrangement shown in Fig. 5 has the advantage that separate identifying wires can be used for the talking con-

nection switches that co-operate with the line finders S^1 , S^2 and for the talking connection switches which co-operate with the selectors W^1 , W^2 . The talking connection switches $V1$, $V2$, $V3$, $V4$ in such an arrangement would only need to have as many identifying wires as there are line finders S^1 , S^2 . In a similar manner the talking connection switches $V1^1$, $V2^1$, $V3^1$, $V4^1$ would only require as many identifying wires as selectors W^1 , W^2 are provided in the particular group. 70 75

When compound switches of the kind illustrated in Figs. 1 to 4 are used, the talking connection switches have to be provided with as many identifying wires as compound switches are furnished. In an exchange in which two connections are to be set up simultaneously, that is where four compound switches have to be provided, four identifying wires would have to be provided for the talking connection switches. 80 85

In smaller exchanges a switching arrangement of the kind shown in Fig. 5 offers the additional advantage that the selector finders WS (Fig. 1) can be dispensed with. Besides in small exchanges where not more than one call is put through at the same instant one single identifying wire would be sufficient for the talking connection switches V1, V2, V3, V4 and another single identifying wire would be sufficient for the talking connection switches $V1^1$, $V2^1$, $V3^1$, $V4^1$.

It must also be mentioned that the compound switches may be provided with separate test relays for setting the switch onto a calling line and for testing a wanted line. 100

Another detail in connection with the starting of the compound switches S^1 , S^2 105 when a subscriber calls will now be described:

In the preceding description an explanation was given of the manner in which a group relay GR is energized when a subscriber calls and it was shown that the armature 9, in brushing past the spring 10, sends a starting impulse to the next compound switch in the group through the wire 19. The armature 9 can only send a further impulse over the wire 19 after it has fallen back. Now it may happen that a second subscriber calls before a compound switch has set its wipers onto the line of the subscriber who first called. The result of this would be that the group relay GR would have no opportunity to fall back in the period between the first and second call, and as the group relay would be kept energized by the current flowing of the line of the second subscriber, this second subscriber would wait in vain to be put through because no second compound switch would be started. To prevent such cases from happening the cut off relay of each subscriber 130

could be provided with a contact, which on the cut off relay being energized, closes the circuit of a relay which is common to the group and which in any case momentarily opens the circuit of the group relay or disconnects it from the bus bar 2. By this means, in cases in which a second subscriber is waiting to be put through whilst a compound switch is setting 10 its wipers onto a line, the armature 9 of the group relay will be caused to retract. It would be immediately de-energized by the current flowing through GR and the line of the second subscriber, and in so doing would 15 send a starting current impulse over the wire 19.

I claim:

1. In a telephone system, calling lines, talking conductors to which the said lines 20 are adapted to be extended, transistorily-engaged two-way call-advancing devices, means for simultaneously advancing a plurality of calls from a plurality of said lines through said call-advancing devices to a 25 plurality of said conductors, and connecting devices for interconnecting talking conductors to which calls have been advanced and the lines from which the calls have proceeded.

2. In a telephone system, calling means, talking conductors to which the said lines are adapted to be extended, transistorily-engaged two-way call-advancing devices, means for simultaneously advancing a plurality of calls from a plurality of the said lines through said call-advancing devices to a plurality of said conductors, and connecting devices for interconnecting each talking conductor to which a call had been advanced 40 only with that particular line from which the call has proceeded.

3. In a telephone system, calling lines, wanted lines, common means for electrically marking both calling and wanted lines, and 45 connecting devices separate from the marking devices for interconnecting marked calling and wanted lines.

4. In a telephone system, calling lines, numerical impulse transmitters associated 50 therewith, wanted lines, talking trunks for effecting talking connections between the calling and wanted lines, selecting devices for selecting wanted lines, transistorily engaged two-way trunks for conducting numerical impulses from calling lines into a 55 plurality of selecting devices simultaneously, means for temporarily associating each transistorily engaged trunk with a talking trunk, and means for connecting each talking trunk 60 only with the same calling line to which the transistorily engaged trunk with which it is temporarily associated is connected.

5. In a telephone system, wanted lines, two-way switches with bank contacts associated with the said wanted lines, calling

means, call-advancing means for advancing calls to the said switches, wipers in the switches adapted to travel over the said bank contacts, a battery, means for connecting said wipers to battery, and means by which in cases of several calls being advanced to the said switches a wiper connected to battery can encounter only one certain bank contact that is also connected to battery.

6. In a telephone system, calling lines, 75 wanted lines, a group of talking-connection line finders, a group of talking connection switches with bank contacts and cooperating wipers, and transistorily engaged two-way switching apparatus for setting the wipers 80 of line finders onto calling line, and the wipers of the said talking connection switches onto wanted lines.

7. In a telephone system, calling lines, 85 impulse transmitters, wanted lines, transistorily engaged numerical switches with bank contacts connected to the wanted lines, circuit arrangements in the numerical switches for receiving a primary and a secondary series of numerical impulses from the impulse transmitters, wipers in numerical switches adapted to be set onto wanted lines in response to the said series of impulses, and means for changing the manner of operation of the switches so that their wipers 90 execute an automatic hunting operation to find a calling line in any of the contact rows in its bank.

8. In a telephone system, lines, calling means associated with the said lines, primary switching apparatus for establishing a plurality of simultaneous talking connections between pairs of the said lines, and separate two-way transistorily engaged secondary switching apparatus for simultaneously advancing a plurality of calls from calling lines and controlling the primary switching apparatus when establishing connections, the primary switching apparatus comprising talking trunks and switching devices for directly connecting these talking trunks to calling lines, and the secondary switching apparatus comprising call-advancing trunks and switching apparatus for directly connecting these trunks 105 also to calling lines.

9. In a telephone system, lines, calling means associated with the said lines, switching apparatus for establishing a plurality of simultaneous talking connections between 110 pairs of the said lines, and separate two-way transistorily engaged secondary switching apparatus for simultaneously advancing a plurality of calls from calling lines and controlling the primary switching apparatus 115 when establishing connections, bells associated with the lines, and ringing circuits confined to the primary switching apparatus 120 for operating the said bells.

10. In a telephone system, a plurality of 130

- calling and wanted lines, a plurality of contacts in which said lines terminate, a trunk, means for electrically identifying a certain one of said contacts as a calling or wanted contact, and means for connecting said trunk with the electrically identified contact.
11. In a telephone system, a plurality of calling and wanted lines, a plurality of contacts in which said lines terminate, a trunk, numerically and nonnumerically operable means for electrically identifying the contact of a wanted line, and means for connecting said trunk to an electrically identified contact.
12. In a telephone system, a plurality of calling and wanted lines, a plurality of contacts in which said lines terminate, a switch, another switch, means for operating said switch in accordance with the designation of a calling or wanted line for selecting the contact of the wanted line; means operated thereupon for actuating said other switch to connect the calling line with the selected contact, and an identifying circuit closed by said other switch for identifying the calling line.
13. In a telephone system, a plurality of calling and wanted lines, a plurality of contacts in which said lines terminate, a switch, another switch, means for operating said switch in accordance with the designation of a calling or wanted line for electrically identifying the contact in which the line terminates and temporarily associating the line therewith, means operative thereupon for actuating the other switch to seize the electrically designated contact and permanently connect the line therewith, and means operative thereupon for releasing said switch.
14. In a telephone system, a plurality of calling and wanted lines, a connector switch having bank contacts connected to said lines, a calling and wanted line marking switch having bank contacts connected to certain bank contacts of said connector, means for operating said line marking switch in accordance with the designation of the line to mark the contact of the line, and means for operating said connector to seize a marked bank contact.
15. In a telephone system, a plurality of calling and wanted lines, a plurality of stationary contacts in which said lines terminate, a set of movable contacts, means for operating said movable contacts electrically to identify a certain stationary contact of a calling or wanted line, other sets of movable contacts, and means for operating the other sets of movable contacts for successively engaging said stationary contacts and for allowing only a certain set to stop at the electrically identified contact.
16. In a telephone system, a plurality of calling and wanted lines, contacts in which said lines terminate, two switches, means operative upon the initiation of a call on one of said lines for actuating one of said switches electrically to identify the contact of the calling line by a certain potential, and means for operating the other switch to seize the electrically identified contact.
17. In a telephone system, a group of calling lines, a trunk line, contact sets in which said calling lines terminate, means operative upon the initiation or completion of a call for electrically identifying a contact set by a certain potential, and means operative thereupon for connecting said trunk line to said contact set.
18. In a telephone system, calling and wanted lines, a plurality of trunk lines, a contact in which a said line terminates, means operative upon the initiation or completion of a call for electrically identifying a contact by applying a certain potential thereto, means for preselecting a trunk line for use, and means for connecting the pre-selected trunk with the electrically identified contact.
19. In a telephone system, a plurality of calling and wanted lines, a plurality of trunk lines, a switch, means operative upon the initiation or completion of a call for actuating said switch to select a calling or wanted line respectively, a second switch connected with said switch, means for operating said second switch to select an idle trunk line, a third switch, and means for operating said third switch to connect the trunk line selected by the second switch with a calling line selected by the first switch.
20. In a telephone system, a plurality of calling and wanted lines, a plurality of trunk lines, a first switch, means operative upon the initiation or completion of a call for actuating said switch to select a calling or wanted line respectively, a second switch connected with said first switch, means for operating said second switch to select an idle trunk line, a third switch, means for operating said third switch to connect the trunk line selected by the second switch with a calling line selected by the first switch, and means operative thereupon for actuating said second switch to select another idle trunk line.
21. In a telephone system, a plurality of calling and wanted lines, a plurality of trunk lines, a first switch, means operative upon the initiation or completion of a call for actuating said switch to select a calling or wanted line respectively, a second switch connected with said first switch, means for operating said second switch to select an idle trunk line, a third switch, means for operating said third switch, to connect the

trunk line selected by the second switch with the calling line selected by the first switch, and means operative thereupon for restoring said first switch and for operating 5 said second switch to select another idle trunk line.

22. In a telephone system, calling and wanted lines, a called line, a trunk line leading towards said called line, a switch, 10 a contact in said switch in which said trunk line terminates, a second contact in said switch in which the calling line terminates, a third contact in said switch, means operative upon the initiation or completion of 15 a call for connecting said third contact with the contact of the calling or wanted line respectively, and means operative thereupon for extending the calling line to said trunk through said first mentioned 20 contact.

23. In a telephone system, calling and wanted lines, link circuits, connecting switches, two-way marking switches for marking both calling and wanted lines, and 25 means for establishing a connection between a said trunk and a marked calling or wanted line through a said connecting switch.

24. In a telephone system, calling and 30 wanted lines, link circuits, two-way connecting switches, two-way marking switches for marking both calling and wanted lines, and means for establishing a connection between a said trunk and a marked calling or wanted line through a said connecting switch.

25. In a telephone system line, numerical 40 switches, line finders with a plurality of test brushes which simultaneously test different lines, means for extending only one said line at a time through a line finder to a numerical switch, and selecting impulse transmitters associated with said lines for sending selecting impulses through said line 45 finders to the numerical switches.

26. The combination with impulse transmitters in a telephone system having calling and wanted lines of a two-way switch comprising passive contacts connected to said 50 lines, groups of active contacts, means for setting an active contact onto a passive contact when the line connected to it makes a call, and means responsive to an impulse transmitter for selecting any said group of 55 active contacts.

27. The combination with impulse transmitters in a telephone system having calling and wanted lines, of a two-way switch comprising bank contacts connected to said 60 lines, sets of wipers that co-operate with different groups of said bank contacts, means for setting a set of wipers onto a bank contact when the line connected to it makes a call, and means responsive to 65 an impulse transmitter for selecting any

of said sets of wipers and setting them onto a said line.

28. In a telephone system, lines, talking trunks, finders with movable contacts connected to said trunks and fixed contacts connected to said lines onto which the movable contacts can be set, a switching device for selecting a free trunk, numerical switches accessible through said trunks, and uni-motional switching apparatus for connecting a calling line through the switching device to a free trunk and for starting the operation of the movable contacts of a finder of this trunk independently of said numerical switches. 70 75

29. In a telephone system, lines, talking trunks, finders with movable contacts connected to said trunks and fixed contacts connected to said lines onto which the movable contacts can be set, a switching device for selecting a free trunk, uni-motional apparatus for connecting a calling line through the switching device to a free trunk and for starting the operation of the movable contacts of the finder of this trunk, and a numerical switch connected to a said trunk and adapted to receive numerical impulses from a calling line during the operation of said movable contacts. 80 85

30. In a telephone system, subscribers' lines, link circuits, two-way connecting devices for connecting a calling line to a link circuit or for connecting the link circuit to a called line, a switching device for selecting a free link circuit, numerical switches accessible through said link circuit, and switching apparatus for connecting a calling line through the switching device to a free link circuit and for starting the operation of a said connecting device independently of said numerical switches. 90 95 100

31. In a telephone system, subscribers' lines, link circuits, connecting devices both for connecting calling lines to the link circuits and for connecting link circuits to wanted lines, a switching device for selecting a free link circuit, switching apparatus for connecting a calling line through a switching device to a free link circuit and for starting the operation of a said connecting device, and numerical switches connected to said link circuits and adapted to receive numerical impulses from calling lines during the operation of said connecting devices. 105 110 115

32. In a telephone system, subscribers' lines, link circuits, connecting devices both for connecting calling lines to link circuits and for connecting link circuits to wanted lines, numerical switching apparatus for marking wanted lines, means for associating a free numerical switching apparatus with a link circuit, and means for preventing a connecting device associated with a numerical switching apparatus from connecting to 125 130

any wanted line excepting the one marked by said associated numerical switching apparatus.

33. In a telephone system, subscribers' lines, link circuits, connecting circuits both for connecting calling lines to link circuits and for connecting link circuits to wanted lines, switching apparatus for marking both calling and wanted lines, means for associating a free switching apparatus with

a link circuit and means for preventing a connecting device associated with a said switching apparatus from connecting to any wanted line or calling line excepting the one marked by said associated switching apparatus. 15

In testimony whereof I have signed this specification.

FRITZ ALDENDORFF.
